UNITED STATES PATENT OFFICE.

GEORGE C. KNAUFF, OF CHICAGO, ILLINOIS.

SOCKET FOR ELECTRIC LAMPS.

1,090,630.

Specification of Letters Patent. Patented Mar. 17, 1914.

Application filed May 26, 1913. Serial No. 769,948.

To all whom it may concern:

Be it known that I, GEORGE C. KNAUFF, citizen of the United States, residing at Chicago, in the county of Cook and State of Illinois, have invented certain new and useful Improvements in Sockets for Electric Lamps; and I do hereby declare the following to be a full, clear, and exact description of the invention, such as will enable others skilled in the art to which it appertains to make and use the same.

My invention relates to lamp sockets and more particularly to sockets having one terminal grounded to the casing so as to carry the currents from the casing to the outer shell of the lamp base, to which shell one end of the filament of the lamp is connected. Owing to variations in the sizes of the commercial brass tubing used for making the shells of the lamp bases and the casings of the sockets, it has not been feasible to obtain a close interfitting of the said shell and casing. Consequently, the lamps used with sockets of this class are usually held firmly only at the projections upon the lamp bases which are generally interlocked with bayonet catch formations upon the socket casings, and are free to rock somewhat about these projections as pivots. In practice, the vibration to which such lamps and sockets are subjected, particularly when used upon automobiles, often causes the lamps to impact against the socket casings with sufficient force to break their filaments. Moreover, the contact between the projections upon the lamp base and the notched portions of the slots in the socket casing is not always adequate for carrying the current to the filament of the lamp.

One object of my invention is to equip the casing of the socket with spring fingers adapted to contact with the sides of the lamp base so as to carry the current from the casing to one terminal of the lamp.

Another object is to so position the points of engagement of the spring fingers with the lamp base as to hold the lamp against lateral motion relative to the casing.

The socket of my invention is particularly adapted for coaction at one end with a lamp having a single central terminal and at its other end with a wire-carrying plug of the type described in my copending application of even date herewith, Serial No. 769,947, and is shown in this embodiment in the accompanying drawings.

In the drawings, Figure —1— is a longitudinal section through a socket equipped with my invention. Fig. —2— is a side elevation of the same. Fig. —3— is an end view of the socket from the line 3—3 in Fig. —2—. Figs. —4— and —5— are perspective views of sockets equipped with alternative embodiments of my invention.

Fig. —1— shows my invention as embodied in a socket having a cylindrical casing 1 of spring metal housing an insulating body 2 which is secured to the casing by a transverse screw 3. Axially mounted within the insulating body 2 is a cylinder 4 having plungers 5 and 6 projecting through perforated caps 7 at the opposite ends of the cylinder, these plungers being continuously pressed outwardly by a spring 8 interposed therebetween. The casing 1 has at each end diametrically opposite slots 9 terminating in enlargements 10 serving as seats for lateral projections 11 upon the metal shell 12 of the base of the lamp used with the socket, the slots 9 serving to guide the said projections to their said seats the said seating of the projections affording a pivotal coupling between the casing and the lamp.

The lamp-engaging end of the socket casing also has fingers 13 punched from the same, these fingers being preferably diametrically opposite each other and circumferentially intermediate the slots 9, or at right angles to the said slots. A part end of each finger 13 is bent inwardly of the casing, so as to slidingly engage the shell 12 of the lamp base when the latter is being inserted into, or withdrawn from, the end of the casing. The casing being of spring metal, the fingers 13 will readily yield or flex to adapt themselves to variations in the size of the shell 12 and will yieldingly bear against the sides of the shell along a line transverse to a plane through the oppositely disposed slots 9. Consequently, the spring fingers will engage the shell of the lamp base in a direction transverse to the axis of the projections 11 about which the lamp may tend to rock when subjected to vibration. By placing the bearing portions 14 of the fingers more endward of the casing than the notches 10 with which the projections interlock, I enable the fingers to exert a considerable pressure upon the sides of the casing, thereby giving an effective lateral support to the lamp. Moreover,

since one terminal of the circuit is grounded to the casing of the socket when the latter is

in use, the spring fingers will carry the current to the metal shell 12 which forms one terminal of the lamp, while the plunger 5 connects the other terminal of the circuit to 5 the axially disposed terminal 15 of the lamp.

Instead of forming the spring fingers at the very end of the casing 1, as in Figs. 1, 2 and 3, they may be positioned somewhat back from the end of the casing, as in Fig. 4.

10 Likewise, their fixed ends may be nearer to the end of the socket than their free ends, as in Fig. —5—, although I prefer the arrangement of Fig. —1— or Fig. —4— as bringing the points of engagement of the fingers and 15 the lamp base considerably more endward than the notches 10.

I claim as new and desire to cover by Letters Patent:

1. In a socket for a lamp having its base 20 equipped with a cylindrical contact shell and diametrically opposite projections upon said shell, a casing having one end larger in bore than the diameter of said shell, the said casing equipped with notched slots receiving 25 the said projections respectively when the shell is inserted in the said end of the casing, the notches of said slots interlocking with the said projections to pivotally couple the lamp to the casing; and spring fingers bent 30 from the said casing at points substantially at right angles to the common axis of the said projections and bearing against the said shell, the resiliency of the said fingers causing the latter to hold the adjacent parts of 35 the said shell out of contact with the end

portion of the said casing and to prevent a forcible impact of the shell against the casing upon relative motion of the lamp and casing about their said pivotal coupling.

2. In a socket for a lamp having its base 40 equipped with a cylindrical contact shell and diametrically opposite projections upon said shell, a casing connected to one terminal of a circuit and having one end larger in bore than the diameter of said shell, the said casing 45 equipped with notched slots receiving the said projections respectively when the shell is inserted in the said end of the casing, the notches of said slots interlocking with the said projections to pivotally couple the 50 lamp to the casing; and spring fingers bent from the said casing at points substantially at right angles to the common axis of the said projections and bearing against the said shell to carry current from the casing to the 55 shell, the resiliency of the said fingers causing the latter to hold the adjacent parts of the said shell normally out of contact with the end portion of the said casing and to prevent a forcible impact of the shell against 60 the casing upon relative motion of the lamp and casing about their said pivotal coupling.

In testimony whereof I have signed my name in presence of two subscribing witnesses.

GEORGE C. KNAUFF.
